UNITED STATES PATENT OFFICE.

JONAS NORTHROP, OF HOPEDALE, MASSACHUSETTS, ASSIGNOR TO THE DRAPER COMPANY, OF SAME PLACE AND PORTLAND, MAINE.

LOOM.

SPECIFICATION forming part of Letters Patent No. 628,228, dated July 4, 1899.

Application filed April 12, 1899. Serial No. 712,774. (No model.)

To all whom it may concern:

Be it known that I, JONAS NORTHROP, a subject of the Queen of Great Britain, residing at Hopedale, in the county of Worcester and State of Massachusetts, have invented an Improvement in Automatic Looms, of which the following description, in connection with the accompanying drawings, is a specification, like letters and numerals on the drawings representing like parts.

This invention relates more particularly to that class of looms provided with automatic filling-supplying mechanism, whereby the transfer of filling is automatically effected at the proper time by or through the failure or more or less partial exhaustion of the filling in the shuttle. Such looms are usually provided with a shuttle-feeler to prevent filling transfer should the shuttle be improperly positioned in the shuttle-box, and heretofore the connections between the shuttle-feeler and the actuating means for the filling-supplying mechanism have been complicated, involving a number of parts.

My present invention has for its object the simplification and more direct action of the means for preventing the transfer of filling when the shuttle is improperly positioned in the shuttle-box.

Figure 1 is a front elevation of a sufficient portion of a loom to be understood, provided with filling-supplying mechanism and having one embodiment of my invention applied thereto. Fig. 2 is a right-hand side elevation of the apparatus shown in Fig. 1, and Fig. 3 is a perspective view of the shuttle-feeler detached.

The loom-frame A, the breast-beam A⁴⁰, the lay A³ having the bottom of one of its shuttle-boxes cut away below the self-threading shuttle S, the filling-supplying mechanism, comprising connected rotatable plates suitably shaped to receive the ends of the filling-carriers b, (see Fig. 1,) the stud f, the trans-ferrer f', mounted thereon and having the depending end f³ and a finger 21, and the shaft d', adapted to be rotated by the movement of the weft-fork in the absence of the filling, are and may be all substantially as shown in United States Patent No. 529,940, granted November 27, 1894, the parts hereinbefore re-

ferred to being operated in practice as hereinafter provided for.

The end f³ of the trans-ferrer has mounted thereon a headed rocker-stud m, surrounded by a spring s, Fig. 1, one end of which is attached to the head of the stud and the other end to the part f³, the spring normally tending to turn the stud in the direction of the arrow 10, Fig. 2, said stud having secured thereto an arm m², provided with a laterally-extended projection or lug m⁴, a notched dog m⁵ being adjustably secured to the arm m² by set-screws 5 and 6, substantially as shown in United States Patent No. 568,455, dated September 29, 1896, said dog when moved into operative position being engaged by a bunter C² on the lay when a change of filling is to be effected.

In order to prevent filling change if the shuttle is improperly positioned in the shuttle-box, the movement of the dog into operative position is controlled by a shuttle-feeler, and in my present invention the shuttle-feeler and the controlling connection between it and the dog is of a very simple character, as will be obvious from an inspection of the drawings, and more particularly Fig. 3 thereof.

The loom-frame is provided with a suitable bracket A¹⁰, on which is pivoted at a a yoke Y, Fig. 3, one of the upturned arms, as y, of the yoke being bent at its upper end to form a shuttle-feeler y⁵, the other arm y' of the yoke being upturned and of sufficient length to directly engage the lug m⁴ on the dog-supporting arm m². The yoke is provided with a lateral stud or projection y², on which is preferably mounted an antifriction-roll y³, (see Fig. 3,) said roll being normally engaged by a detent-finger d⁵, fast on the rock-shaft d' and normally maintained in the position shown by a strong spring d³, attached at its ends to the detent-finger and to the frame, respectively, as herein shown.

Referring to Fig. 2, it will be noticed that when the shuttle-feeler and its rigidly-attached arm y' are in normal position the roll y³ will be between the fulcrum a of the yoke and the lug m⁴ of the dog-support, and the spring d³ being stronger than the spring s the dog will be maintained in inoperative position so long as the detent-finger d⁵ operatively en-

gages the yoke. Upon failure of the filling, however, the rock-shaft d' is turned in the direction of the arrow 30, Fig. 2, as in the patent referred to, against the stress of the 5 spring d^3 , so that the detent-finger d^x releases the yoke and permits the shuttle-feeler to move toward the lay to detect the position of the shuttle, such detecting movement being effected in the present case by or through the 10 action of the spring s , and if the shuttle is properly positioned in the shuttle-box the feeler is permitted to complete its full detecting movement, so that the controlling-arm y' is moved sufficiently to permit the swinging 15 of the dog m^x into position to be engaged by the bunter C^2 as the lay comes forward. Such engagement of the dog and bunter effects a change of filling. Should the shuttle be improperly positioned, however, it will be engaged 20 by the feeler, so that the latter can complete its detecting movement, and the controlling-arm y' thus operates to prevent the movement of the dog into operative position.

25 From the foregoing it will be manifest that the connection between the shuttle-feeler and the actuating means for the filling-supplying mechanism is of the simplest character, and this will be especially obvious when the present 30 construction is compared with that shown in Patent No. 568,455, referred to, or United States Patent No. 529,943, dated November 27, 1894.

35 My invention is not restricted to the particular construction and arrangement of parts herein shown, as the same may be modified or rearranged without departing from the spirit and scope of my invention, for, so far as I am aware, it is broadly new to control 40 the actuating means for filling-supplying mechanism by a controlling member rigidly connected with the shuttle-feeler and in direct engagement with said actuating means.

Having described my invention, what I 45 claim as new, and desire to secure by Letters Patent, is—

1. In a loom, the lay having a shuttle-box; filling-supplying mechanism; actuating means therefor comprising a spring-actuated 50 dog and a bunter to coöperate therewith; a shuttle-feeler having a rigidly-connected arm in direct engagement with and to normally maintain the dog inoperative, and a detent for the feeler, operated upon failure of the 55 filling to release the feeler and through the said arm to permit movement of the dog into operative position when the shuttle is properly positioned in the shuttle-box.

2. In a loom, the lay having a shuttle-box, 60 a filling-transferrer, a pivotally-mounted dog

operatively connected therewith; a spring to move it into operative position; and a bunter to coöperate with the dog; a shuttle-feeler having a rigidly-connected arm in direct engagement with and to normally retain the dog 65 inoperative against the action of the spring, and means actuated by failure of the filling to release the feeler and permit detecting movement thereof, and movement of the dog into operative position when the shuttle is 70 properly positioned in the shuttle-box.

3. In a loom, the lay having a slotted shuttle-box; filling-supplying mechanism; actuating means therefor, including a dog and a bunter; a shuttle-feeler provided with a rigid 75 arm in direct engagement with and to control the position of the dog; means to move the dog into operative position and through the arm to effect detecting movement of the feeler, and means actuated by failure of the 80 filling to release the feeler.

4. In a loom, the lay; a filling-carrier trans- 85 ferrer having a depending end; a dog pivoted thereon; a bunter; a spring to move the dog into operative position; a shuttle-feeler having an upturned, rigidly-connected arm to directly engage and move the dog against the actuating-spring; and means to normally maintain the feeler and dog inoperative, said means being actuated upon failure of the fill- 90 ing to release the feeler.

5. In a loom, the lay; a filling-carrier trans- 95 ferrer having a depending end; a dog pivoted thereon and provided with a projection; a bunter; a spring to move the dog into op- 100 erative position; a shuttle-feeler having an integral controlling-arm in engagement with said projection, whereby movement of the dog is controlled by the feeler; a stud carried by the feeler, and means, including a detent-fin- 100 ger in engagement with said stud, actuated upon failure of the filling to release the shuttle-feeler.

6. In a loom provided with filling-supply- 105 ing mechanism, actuating means therefor, a shuttle-feeler having a rigidly-attached mem- 110 ber in direct engagement with and to control the operation of said means, and means actuated by failure of the filling to release the feeler and thereby permit the said actuating means to operate when the shuttle is prop- 110 erly positioned.

In testimony whereof I have signed my name to this specification in the presence of two subscribing witnesses.

JONAS NORTHRUP.
